(57) **CLAIM**

The ornamental design for an air intake for helmet, as shown and described.

DESCRIPTION

FIG. 1 is a front perspective view of an air intake for helmet showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is an enlarged right side view thereof; and,

FIG. 8 is an enlarged cross-sectional view taken along line 8-8 in FIG. 3 thereof.

The broken lines illustrate portions of the air intake and form no part of the claimed design. The dash-dotted lines denote the boundary of the claim and form no part of the claimed design.
